UNITED STATES PATENT OFFICE.

WALTER SYDNEY ROBERTS, OF ORMSKIRK, ENGLAND, ASSIGNOR OF ONE-HALF TO
THE RAILWAY SIGNAL COMPANY LIMITED, OF LONDON, ENGLAND, A BRITISH
COMPANY.

TOKEN SYSTEM.

Application filed April 6, 1925, Serial No. 21,036, and in Great Britain April 14, 1924.

This invention relates to instruments for issuing and receiving tokens in the form of staffs, tablets, or the like for regulating railway traffic, and has for its object to provide improved arrangements of this character which shall be applicable to single or double line railways operating upon either the absolute or permissive system of working.

In single line railways the staffs or other tokens employed for authorizing the passage of traffic along a section of the track, while different for different sections, are the same for both directions of movement, that is to say, the staffs or tokens employed for authorizing the passage of trains or vehicles in the up direction are the same as those for the down direction, so that when the permissive system of working is in operation in which a number of trains travelling in the same direction are permitted to occupy simultaneously a single section of the track, there is a possibility of the staff on the authority of which a train passes through the section being issued when the train reaches the end of the section to a train proceeding in the opposite direction, since the staff is equally valid authority for a train travelling in either direction.

In order to overcome this difficulty, according to the present invention, each staff or other token is appropriate not only to a particular section of the track but to one direction only of travel within that section, thus providing what may be termed a unidirectional token system of control of traffic.

For the same general purpose and according to a further feature of the invention the receptacle for the staffs or other tokens at the instrument controlling their issue and reception is provided with arrangements for preventing the issue in the ordinary manner at each instrument of tokens authorizing movement in one direction and may be provided with separate compartments for the tokens for the two directions of movement.

For convenience in description the staffs or other tokens authorizing movement from one end of the section to the other will be hereinafter referred to as up tokens, and those authorizing movement in the opposite direction as down tokens, it being understood that in the case of the token instrument at the station at one end of the section the up

tokens are issued to a train on departure from that station, and are received by the token instrument at the station at the other end of the section upon the arrival of the train. Conversely, the down tokens are issued from the token instrument at the latter station and are received by the token instrument at the first station. The "departure" token at one instrument thus becomes an "arrival" token at the other instrument and vice versa, as will be readily understood by those skilled in the art.

The invention is illustrated by way of example in the accompanying drawings, of which

Figure 1 is a diagrammatic view of the two staff instruments provided one at each end of a single line section of railway track;

Figures 2 and 3 are views of an up staff and a down staff respectively, which may be employed with the instruments of Figure 1;

Figure 4 is a sectional front view of a portion of the head of one of the staff instruments;

Figure 5 is a side view of a portion of the mechanism shown in Figure 4;

Figure 6 is a view in horizontal section of the lower portion of one of the staff instruments of Figure 1;

Figure 7 is a view in front elevation of a permissive staff instrument embodying the invention;

Figure 8 is a side view of the lower portion thereof;

Figure 9 is a view in front elevation of an up staff magazine adapted to be employed in connection with the staff instruments;

Figure 10 is a plan view thereof;

Figures 11 and 12 are views similar to Figures 9 and 10 respectively, but of a down staff magazine;

Figure 13 is a view in side elevation of the key provided on the staff instruments and magazines;

Figure 14 is a sectional view of the locking slides with which this key co-operates, and Fig. 15 is a detail of the bolt locking mechanism.

Referring now to the drawings, it will be seen that two staff instruments are shown in Figure 1 as arranged in the usual manner at the ends A, B of a section of track. Each

of these instruments is provided with a slotted staff receptacle arranged in the usual manner in the lower part of the instrument, this receptacle being however, subdivided into two compartments, the slots indicated at 1 being adapted to accommodate up staffs only and those indicated at 2 to accommodate down staffs only. This selective action is effected by the cross-sectional form 10 of the receptacle slots, as shown in Figure 6. The up staff shown in Figure 2 is provided with four operating collars or rings 3, 4, 5, 6, the down staff shown in Figure 3 being similarly provided with collars or rings 7, 8, 9, 10, which are, however, differently spaced along the staff from the collars of the upstaff. The up and down staffs are further distinguished by tablets 11, 12 of different distinctive shapes. It will be seen by reference to Figure 6 that the receptacle slots 1 are provided with recesses 27, 28, 29, 30 to accommodate the rings 3, 4, 5, 6, respectively of the up staff, while the slots 2 are provided with recesses 31, 32, 33, 34, to accommodate the rings 7, 8, 9, 10 respectively of the down staff.

Each staff instrument while permitting the insertion of both up and down staffs is, according to a still further feature of the invention, so constructed that only one type of staff can be issued therefrom in the usual manner, that is to say, the staff instrument at A station may receive both up and down staffs but can only issue up staffs while the instrument at the other station B can receive both up and down staffs but can only issue down staffs.

At each instrument the withdrawal of the staffs the issue of which in the usual manner is prevented, that is to say, the down staffs at the first station and the up staffs at the second station, is arranged to be effected by a magazine.

Separate magazines are provided for the up and down staffs and are so constructed as to receive only the particular type of up and down staffs for the section to which they correspond.

The insertion and withdrawal of the staffs into and from the staff instruments may be arranged to be controlled in the manner above described, as shown in Figures 4 and 5, in which the head of the staff instrument is shown as provided with the usual spindle 13 and locking discs, one of which is indicated at 14. The usual locking pawls 15, 19 for these discs are pivoted at 16 and 20 respectively, the pawl 15 being provided with a locking member 22 which is raised out of engagement with a notch 23 in the disc 14 when an up staff is inserted into or removed from the instrument. The function of the pawl 19 is to return the pawl 15 positively to its normal or locking position 60 as the staff passes into the passage 25 on its

way to the staff receptacle, a projection 21 on the pawl 19 engaging with the toe 18 of the pawl 15 for this purpose.

The rib 17 usually provided on the pawl 15 is cut away adjacent to the toe 18 as shown, 70 so that the pawl 15 can only be raised by the collar 4 on the up staff engaging with the toe 18, there being no corresponding collar on the down staff. An up staff can thus either be inserted into or removed from the 75 instrument of Figure 4, the collar 4 on this staff unlocking the pawl 15 to permit the issue of the staff. Upon attempting to remove a down staff, however, the collar 8 will register with the cut away portion of the 80 rib 17 so that this staff cannot release the pawl 15 to permit the issue of a down staff.

At the B instrument, on the other hand, the rib 17 is not cut away at the end, the toe 18 being cut away so as not to be engaged 85 by the collar 4 of an up staff, whereas the collar 8 of a down staff will engage with the uninterrupted rib 17 and thus actuate the pawl 15. An up staff cannot thus be removed from the B instrument. 90

The insertion of both up and down staffs into either instrument is, however, permitted in the usual manner, as will be readily apparent to those skilled in the art.

Referring now to Figures 7 and 8 it will be seen that the head 26 of the staff instrument is supported upon the staff receptacle 35 which is mounted upon a base 36. The outer slot of each of the slot receptacles 1, 2 for the up and down staffs respectively 100 communicate with removal apertures in the front of the base 36, the aperture for the up staffs being indicated at 37, and that for the down staffs at 38. The apertures 37, 38 are provided with a sliding bolt 39 adapted 105 when in its normal position, as shown in Figure 7, to prevent the passage of staffs through the apertures 37, 38, but when moved to the right or left to free the aperture 37 or the aperture 38 respectively so as 110 to enable staffs to be withdrawn from the slots 1 or the slots 2 of the receptacle 35. The bolt 39 is arranged to be operated manually by a knob 40 and is normally locked in the position shown by the lock mechanism shown in Fig. 15 and hereinafter described, and adapted to be unlocked by a key carried in a staff magazine, this key entering a key slot 41 for this purpose. A second key 42 is mounted in the front of the base 36 and is adapted to be moved outwards by means of a knob 43 so as to project beyond the front face of the base 36 to enter a key slot in the magazine. 115

Adjacent to the lower end of the outer slot 1 and of the outer slot 2 a pivotally mounted supporting element is provided adapted to carry the column of staffs above it, this supporting element comprising a pair of cams 45 pivoted at 46 to the receptacle 35 120

and connected together by a cross bar 49 serving as an operating handle and a stop. A projection 47 on each of the cams 45 is acted upon by a spring 48 in such a manner 5 as normally to maintain the cams 45 in the position shown, a space being left in the receptacle below the supporting element so as to enable a staff to be readily transferred from the magazine to the receptacle without 10 this action being impeded by the weight of the column of staffs already in the receptacle.

A table 44 extends outwards from the front of the base 36, for supporting a magazine in position during the transference of staffs between the instrument and the magazine, the upper surface of the table 44 being provided with a peg or projection 89 adapted to enter a corresponding recess in the 15 base of the magazine (indicated at 59 in Figure 9) adapted to co-operate with the instrument, thus preventing magazines appropriate to other track sections from being employed, the magazine for down staffs being shown in Figures 9 and 10.

Referring to these figures it will be seen that the magazine comprises a body portion 50 provided with a curved slot 51 for accommodating the staffs which can only enter 20 or leave the slot 51 through an aperture 57 of sufficient diameter to permit the collars or rings on a staff to pass longitudinally therethrough. The aperture 57 is normally obstructed by the end of a slide or bolt 52 which is normally locked in the position shown by a lock mechanism adapted to be released by the insertion of the key 42 shown 25 in Figure 7 into the key slot 53 of the locking mechanism on the magazine.

A key 54 is provided in the magazine which, when the latter is in position on the table 44 of the staff instrument, is adapted 30 to enter the key slot 41 and to unlock the slide 39. The key 54 is normally in a retracted position within the body 50 of the magazine and is provided with a knob 55 by means of which the key may be moved 35 into its projected position to enter the key slot 41. This outward movement of the key 54 is, however, prevented by means of a projection 58 on the slide 52 so long as the latter is in its closed position shown in Figure 9, so that the key 54 can only be projected when the magazine is in position on 40 the instrument, since only under these conditions can the slide 52 be moved to its open position, being released by the key 42 on the instrument. When, therefore, the magazine 45 is removed from the staff instrument, the magazine key 54 is always necessarily retracted within the body of the magazine, so as to be protected from injury and inaccessible for inspection, thus preventing 50 any possibility of the key being improperly reproduced. The magazine body 50 is pro-

vided with a handle 56 for convenience in transport.

The up staff magazine shown in Figures 11 and 12 is similar to the down staff magazine above described with reference to Figures 9 and 10, except that the aperture 67 in the up staff magazine is adapted to register with the aperture 37 in the staff instrument.

Referring now to Figure 13, it will be seen 75 that the keys employed on the staff instruments and magazines are provided with indentations 70, 71, 72, adapted to engage with and to operate plungers 76, 77, and 78 in the locking mechanism shown in Figure 14. Intermediate plungers 79, 80 and 81 abut 80 against the plungers 76, 77 and 78 respectively, and are actuated by lower plungers 82, 83, 84 respectively, provided with controlling springs 85, 86, and 87.

By reference to Figure 14, it will be evident that when the key is withdrawn from the key slot 75 the plungers 79, 80, 81 and 82, 83, 84 lock the slide 74 to the body of the lock casing 73, whereas, when the proper key is inserted into the key slot 75, the ends of the plungers 79, 80, 81 which are each of the same axial length as the thickness of the slide 74 lie flush with the upper and lower faces of the slide 74 so that the latter is 95 free to be displaced.

When the slide 74 is thus displaced the key is evidently prevented from being withdrawn from the key slot 75 until the slide 74 is returned to its normal position, the plungers 76, 77 and 78 engaging the indentations 70, 71, 72 respectively.

The slide indicated at 74 in Figure 14 corresponds to the slide 39 of Figure 7, and to the slide 52 of Figures 9 and 10, the keys 105 indicated at 42 in Figure 7 and at 54 in Figure 9 being of the general form shown in Figure 13.

In operation it will be understood that the magazine shown in Figures 9 and 10, for instance, is first placed in position on the table 44 of the staff instrument shown in Figures 7 and 8. The key 42 is then caused by operating its knob 43 to enter the key slot 53 in the magazine and thus unlock the slide 110 52. The latter can then be moved into its open position to free the aperture 57 at the same time permitting the key 54 to be projected forward by means of its knob 55 so as to enter the key slot 41 on the staff instrument. The insertion of the key 54 unlocks the slide 39 which can then be moved to free the aperture 38.

The co-operating apertures 38 and 57 on the instrument and magazine respectively 115 being thus freed the staffs in the slot receptacles 2 can be transferred to the magazine, each staff being moved from the slots 2 in the staff instrument past the right hand pair of cams 45 by moving these cams out- 120 125 130

wards by means of the cross bar 49. Each staff in turn is thus caused to register with the aperture 38 in the base 36 of the staff instrument and is then moved longitudinally forward so as to enter the aperture 57 in the magazine, and thus pass into the slot 51. As many staffs as desired can thus be transferred from the staff instrument to the magazine, and during this operation it will be understood that the magazine cannot be removed from the table 44 on the staff instrument, as the magazine and base 36 of the instrument are held locked together by the action of the keys 42 and 54. When the transference of the desired number of staffs has been completed, the key 54 in the magazine is withdrawn by means of the knob 55, and the slide 52 is moved into its closed position. The slide 39 on the staff instrument is then restored to its normal position as shown in Figure 7 and the key 42 is withdrawn from the key slot 53 on the magazine by means of the knob 43.

Owing to the closed position of the slides 52 on the magazine and 39 on the staff instrument, it will be evident that both the magazine and the instrument are again locked so as to prevent the passage of staffs through the apertures 38 and 57 and it will be noted that the slide 39 is provided with a spring actuated pin 88, the rounded or pointed end of which is adapted to enter a shallow depression of corresponding form in the slide 39, so as to define the closed position of the slide as shown in Fig. 15.

The magazine can now be removed from the instrument and transferred in any convenient manner to the instrument at the other end of the section where the staffs within the magazine may be transferred to the staff instrument in a similar manner to that above described.

The same operations in connection with the transference of up staffs can evidently be effected by the employment of the appropriate magazine shown in Figures 11 and 12, the staff aperture 67 of this magazine being adapted to register with the staff aperture 37 shown in Figure 7.

In the case of systems intended for both absolute and permissive block working on single lines, the tokens may be further appropriated into permissive and absolute tokens for each direction, the token receptacles in the instruments and the magazines for the transference of non-issuable tokens from one instrument to the other being similarly appropriated to one of the four types of token employed, viz, up permissive tokens, up absolute tokens, down permissive tokens, and down absolute tokens. Each of the token instruments will in this case be provided with separate compartments or receptacles for the different types of token and the magazine will similarly be adapted to accommo-

date only one type of token, as will be readily understood.

In the case of double line railways having separate lines for traffic in the two directions, separate token instruments for up and down tokens may be provided at each end of a section, the up instrument at one end being adapted to issue tokens and the up instrument at the other end to receive tokens, the down instrument at the latter end being adapted to issue tokens, and the down instrument at the opposite end to receive tokens or in order to reduce the number of instruments required the up and down instruments at each end of the section may be combined so as to issue up tokens and receive down tokens or vice versa.

In the case of double line railways the standard electrical release mechanism will not be provided in the receiving instruments and the staffs accumulated at each of the instruments will be transferred to the opposite end of the section by means of magazines as above described.

The construction and arrangement of the instruments and magazines will be modified accordingly in the case of double line systems or in the case of systems in which the staffs are further subdivided into different types as above explained, and in these and other respects the invention is not limited to the particular arrangements above described which may be varied as will be readily understood, to meet particular conditions.

Having now described my invention, what I claim as new and desire to secure by Letters Patent, is:

1. In a token instrument for railways, the combination of a plurality of tokens authorizing travel in one direction only, a plurality of tokens authorizing travel in the opposite direction only, a token instrument for receiving both of said types of token, and controlling means on said instrument actuated by both types of tokens to permit the insertion of said tokens into the instrument and actuated by one type of token only to permit the removal of said token.

2. In a token instrument for railways, the combination of a plurality of tokens authorizing travel in one direction only, a plurality of tokens authorizing travel in the opposite direction only, a token instrument for receiving both of said types of token, a controlling device on said instrument traversed by both types of token during insertion, a device for mechanically locking said controlling device, and means actuated by both of said types of token for releasing said locking device when inserted into said instrument and actuated by only one of said types of token when removing a token from said instrument.

3. In a token instrument for railways, the

combination of a plurality of different types of tokens, a token instrument for receiving tokens of all of said types, and controlling means on said instrument actuated by tokens of all of said types to permit the insertion of said tokens into the instrument and actuated by one type of token only to permit the removal of a token of said type.

4. A magazine for use in connection with a token system as claimed in claim 3, comprising a key adapted to enter a corresponding lock on a token instrument, in which the key is retracted within the magazine except when the latter is in position on the instrument, for the purpose specified.

5. A token instrument and magazine therefor for use in connection with the system claimed in claim 3, and comprising keys on

the instrument and magazine adapted to enter corresponding locks on the magazine and instrument respectively, in which the locks are of the subdivided plunger type, substantially as and for the purpose specified.

6. A magazine for use in connection with a token system as claimed in claim 3, comprising a key adapted to enter a corresponding lock on the token instrument, in which the projection of the key from the magazine is arranged to be prevented until a slide, normally preventing the transference of tokens to or from the magazine, is moved to its inoperative position, substantially as and for the purpose set forth.

In testimony whereof I have hereunto set my hand.

WALTER SYDNEY ROBERTS.
